Patented Oct. 6, 1857.

UNITED STATES PATENT OFFICE.

SANFORD KINGSBERRY, OF CARROLLTON, GEORGIA.

MACHINE FOR SHUCKING AND SHELLING CORN.

Specification of Letters Patent No. 18,342, dated October 6, 1857.

To all whom it may concern:

Be it known that I, SANFORD KINGSBERRY, of Carrollton, in the county of Carroll and State of Georgia, have invented a new and Improved Machine for Shucking and Shell-
5 ing Corn; and I do hereby declare that the following is a full and exact description thereof, reference being had to the accompanying drawings, making a part of this
10 specification.

In the said drawings, Figure 1, is a top view, and Fig. 2, a side elevation of my improved machine for shucking and shelling corn; and Figs. 3, 4, 5, and 6, are representations of detached portions of said machine.

Similar letters indicate like parts in each drawing.

A suitable supporting frame for my im-
20 proved machine for shucking and shelling corn, is clearly represented in the accom-
panying drawings; this may be constructed
of any suitable material, and in any manner
that will give it the proper degree of
25 strength and stability.

Upon a suitable driving shaft D, which must be placed in a horizontal, or nearly a horizontal position, I secure a strong wheel A, of forty-two inches in diameter or there-
30 about. One or both sides of said wheel I arm with peculiarly arranged lateral teeth; viz; at the distance of some eight or ten inches from the center of the face of said wheel, commences the innermost of two,
35 three, or four annular rows g, g, of teeth, which gradually increase in length from the innermost to the outermost of said rows; and outside of the said annular rows of teeth g, g, the face of the wheel is armed with
40 alternating fan-shaped series of teeth f, f, which gradually increase in length as they pass outward to the periphery of the wheel.

In practice, I find that a suitable length for the actuating teeth on the face of the
45 wheel A, is to give the inner row of teeth g, the length of half an inch, and the extreme outermost teeth f, the length of one inch and a half, and to have the intermediate teeth gradually increase in length from
50 the former to the latter of the said enumerated teeth. I also find that the machine works well in practice, when the respective

series of teeth f, f, occupy about the same space as the blank surfaces between said series of teeth. I have also discovered that 55 when the entire face of the wheel A, is armed with teeth, the said teeth very soon fill up with shucks and the machine becomes inoperative until its actuating teeth have been cleaned of the said clogging shucks. 60

At the side of the face of the wheel A, and as near to its shaft as practicable, I secure to the frame of the machine, the vertical tapering concave B, whose shape is represented by Figs. 1, 5, and 6, of the accompanying drawings; the inner surface of said concave being of such a shape that all parts thereof will be equidistant from the extremities of the respective series of teeth f, and g, which project from the face of the 70 wheel A. Two of the said concaves can be used in conjunction with the toothed face of the wheel A; viz; one placed on each side of the shaft of the said wheel. Both sides of the wheel A, may be armed, with teeth, 75 and therefore, four of the vertical tapering concaves may be used in combination with one doubly-armed actuating wheel.

The lower extremity of the tapering con-
cave B, should extend but a very short dis-
tance below the shaft of the wheel A. When
the lower end of the said concave is allowed
to extend much below the axis of the wheel
A, the cobs, I find, are broken into small
pieces by the double action of the actuating 85 teeth.

The unshucked ears of corn must always be inserted butt-end foremost into the con-
cave B; and when so inserted, if a suffi-
ciently high speed is at the time imparted to 90 the wheel A, the shucks will be at once
severed from the ear and pass out at the
side of the upper portion of said concave,
while the ear will descend and will lose
every kernel of its corn before its cob 95
emerges from the lower end of said concave;
the shucking operation being accomplished
by the outer series of teeth f, f, and the oper-
ation of shelling being principally accom-
plished by the annular rows of teeth g, g. 100

What I claim as my invention and desire to secure by Letters Patent, is—

The combination of the toothed face, or faces, of the wheel A, with the tapering con-

cave, or concaves B, when the respective series of actuating teeth on the face, or faces, of the wheel A, are proportioned and distributed substantially as herein set forth, and for the purposes specified.

The above specification of my new and improved machine for shucking and shelling

corn, signed and witnessed this eighth day of August 1857.

SANFORD KINGSBERY.
